MOBILE AERIAL WORK PLATFORM

John L. Grove, Greencastle, and Paul K. Shockey,
McConnellsburg, Pa., assignors to Fulton Industries,
Inc., McConnellsburg, Pa.

Filed June 29, 1971, Ser. No. 158,148

Term of patent 14 years

Int. Cl. D12—13, 09

U.S. Cl. D14—3 R

FIG. 1.

FIG. 2

FIG. 3

FIG. 1 is a perspective view of the mobile aerial work platform embodying our new design with the platform shown in lowered position.

FIG. 2 is a rear elevation of the mobile aerial work platform taken from the left-hand side of FIG. 1.

FIG. 3 is a side elevation of the mobile aerial work platform shown in FIG. 1.

FIG. 4 is a front elevation of the mobile aerial work platform taken from the right-hand side of FIG. 1.

FIG. 5 is a perspective view of the mobile aerial work platform embodying our new design with the platform shown in elevated position.

FIG. 6 is a perspective view taken from the opposite side of the mobile aerial work platform shown in FIG. 5.

We claim:

The ornamental design for a mobile aerial work platform, as shown and described.
